UNITED STATES PATENT OFFICE.

JOHN J. SCHILDER, OF FORT WORTH, TEXAS.

PUMP-OPERATING APPARATUS.

1,211,764.

Specification of Letters Patent. Patented Jan. 9, 1917.

Application filed May 11, 1916. Serial No. 96,745.

To all whom it may concern:

Be it known that I, JOHN J. SCHILDER, citizen of the United States, residing at Fort Worth, in the county of Tarrant and State of Texas, have invented certain new and useful Improvements in Pump-Operating Apparatus, of which the following is a specification.

This invention pertains to new and useful improvements in pump operating apparatuses.

In carrying out the invention a mechanism is provided which involves a flexible connection attached to one of the reciprocating pumping elements and a pair of flexible connections attached to the other reciprocating pumping element are coiled with the first connection about a common operating member so that the pair of connections are unwound as the single connection is wound and vice-versa, whereby the pumping elements are reciprocated in opposite directions and one is moved in one direction while the other is moved in the opposite direction.

The flexible connections being wound or coiled on a common operating member it is obvious that by reversing the revolution of this member periodically that the winding and unwinding of the respective connections is relatively reversed periodically by suitable mechanism; or when a connection has been found to move its pumping element to the end of its stroke the motion is reversed and the connection unwound, the other connections being at the same time wound and vice-versa.

Other features of the invention will be apparent from a perusal of the following specification and the invention will be more readily understood by reference to the accompanying drawings, wherein:

Figure 1 is a vertical sectional view of the apparatus, Fig. 2 is a transverse sectional view, and Fig. 3 is a plan view.

In the drawings the numeral 1 designates a frame work having upper sills 2 on each side and lower sills 3 thereunder. A transverse guide shaft 4 is journaled on the sills 2 and a similar shaft 5 is journaled immediately thereunder on the sills 3. Under the shafts the pumping elements 6 and 7 respectively are located. A pair of drums or guide spools 8 are mounted on the shaft 5 and spaced apart, while a single spool 9 is mounted on the shaft 4 in intermediate relation to the spools 8. A single flexible con-

nection 10 is coiled once around the spool 9 and has its lower end fastened to the member or element 6; while a pair of flexible connections 11 each coiled once around one of the spools 8 have their lower ends connected to the element 7.

An actuating or operating shaft 12 is journaled on the sills 2 and has fixed thereon a central drum 13 on each side of which are fastened drums 14. The connection 10 is coiled about the drum 13 and the connections 11 are coiled in the opposite direction around the drums 14, said connections being arranged so that when the one 10 is wound up the pair 11 are unwound. Consequently the connections are continuously winding and unwinding as the shaft 12 is revolved. On each end of the shaft 12 a gear 15 is fixed and meshes with a similar gear fixed on the adjacent end of the shaft 4, while a gear 17 fixed on the end of the shaft 5 meshes with the gear 16. These gears are all equal in diameter and it is obvious that the gear 15 driving the gear 16 which in turn drives the gear 17, the shafts 4 and 5 will be oppositely revolved whereby the spool 9 will wind while the spools 8 are unwinding the connection.

Motion being imparted to the shaft 12 and the same revolved in the direction indicated by the arrow in Fig. 1 it will be seen that the connection 10 will be wound on the drum 13 and the connections 11 unwound from the drums 14, whereby the element 6 will be elevated and the element 7 lowered. When the drum 13 has wound a certain length of the connection 10 the member 6 will have reached the upper end of its stroke and the drums 14 will have unwound enough of the connections 11 to lower the element 7 to the end of its stroke, consequently to continue the operation the shaft 12 must be reversed so that the drum 13 will start to unwind the connection 10 and the drums 14 to wind the connections 11; whereby the element 6 is lowered and the element 7 elevated. A double acting pump operating apparatus of a simple nature is had and a comparatively long stroke will be produced by this apparatus.

It will be apparent that various forms of well known reversing devices may be employed for driving the shaft 12 and I have illustrated one of such in the drawings, but wish to point out that its details form no part of the invention and that any means

for the purpose can be used. The device comprises a shaft 20 journaled on the sills 2 and having fixed on its ends pinions 21 which mesh with and drive the gears 15. On the shaft 20 are three pulleys 22, 23 and 24 respectively the center one of which is fixed on the shaft while the others are loose, the central pulley 23 thus becomes the driving pulley and revolves the shaft 20. A counter shaft 25 is also mounted on the sills 2 and driven from a suitable source. A broad faced pulley 26 is fastened on this shaft and two belts 27 and 28 are driven thereby, the belt 28 being crossed and running on the loose pulley 24 when the straight belt is driving the pulley 23. To reverse the shaft 20 the belts are shifted so that the belt 27 is moved on to the pulley 22 and the cross belt 28 on to the pulley 23. For effecting this shift a properly timed mechanism should be employed. In carrying out this feature the pulleys 23 and 22 are connected by means of a ratchet 29 or other means so that when the belt 27 is driving the pulley 23 the latter will drive the pulley 22, but when said belt is shifted on to the pulley 22 and the pulley 23 is being driven by the belt 28, said pulley 23 will not impart motion to or interfere with the revolution of the pulley 22. A clutch 30 is engaged with the pulley 22 and is mounted on a sleeve 31 loosely confined on the shaft 20 and carrying a worm 32. This worm drives a gear 33 mounted on a shaft 34 supported by cross timbers 35 resting on the sills 3. It is obvious that the gear is constantly driven in the same direction. A supporting frame 38 is mounted on the sills 2 and carries a transverse shifting rod 35 from which belt shifters 36 depend and straddle the belts. A hanger 37 depends from the frame 38 and is also supported on the shaft 34. Trip pieces 39 and 40 respectively are pivoted on the hanger relatively at the top and bottom of the gear and in the path of a pin 41 projecting from the side of the gear. The tripping pieces are pivoted

to a link 42 and are arranged so that when the pin 41 swings one out of its path said link swings the other into the path of said pin. The upper end of the link is pivoted to a bell crank lever 43 which latter is pivoted to the shifting rod 35. It will be seen that each time a tripping piece is swung the rod 35 will be moved and the belts shifted, this will occur at each half revolution of the gear 33.

What I claim, is:

1. In an apparatus of the class described, the combination with a support and oppositely reciprocating pumping elements, of a flexible connection attached to one of said elements, and a second flexible connection attached to the other pumping element, a pair of guide shafts each having one of the connections coiled thereabout, an operating shaft, drums mounted on the operating shaft on which the connections are coiled in opposite directions, a train of gears mounted on the shafts so that the guide shafts are revolved in opposite directions, and means for driving the operating shaft including means for intermittently reversing the transmission of motion thereto.

2. In an apparatus of the class described, the combination with a support and oppositely reciprocating pumping elements, of a flexible connection attached to one of said elements, and a second flexible connection attached to the other pumping element, a pair of guide shafts one disposed above the other, spools mounted on the guide shafts each having one of the connections coiled thereabout, an operating shaft, drums mounted on the operating shaft on which the connections are coiled in opposite directions, a train of gears mounted on the shafts so that the guide shafts are revolved in opposite directions, and means for driving the operating shaft including means for intermittently reversing the transmission of motion thereto.

In testimony whereof I affix my signature.

JOHN J. SCHILDER.
